UNITED STATES PATENT OFFICE

MORGAN PARKER, OF NEW YORK, N. Y.

MANUFACTURE OF DETACHABLE BLADES

Original application filed March 7, 1927, Serial No. 173,528. Divided and this application filed February 20, 1928, Serial No. 255,722. Renewed October 2, 1930.

This invention relates to the manufacture of replaceable blades or cutting edges for scissors. Scissors and shears which are in constant use must be continually resharpened. This is not only expensive and time-consuming, especially if the blades are ground to a properly serrated cutting edge, as for barbers' shears, but after a time the grinding wears the blades to such a condition that the scissors must be discarded. In some instances too it may be difficult to secure the services of a skillful grinder, so that the scissors must either be poorly ground or be used when too dull for efficient cutting. Furthermore, the blades of the common type of scissors should be made of high grade cutlery steel throughout if they are to present and retain a keen cutting edge after each grinding. This is expensive and involves drop-forging difficulties.

It was early recognized that a two-part blade would solve some of these difficulties. A tool steel cutting blade welded or mechanically attached to a softer metal shank simplifies the drop-forging problem and makes a cheaper instrument, but the resharpening problem still persists. Such blades when mechanically secured to the shank, are comparatively heavy, are ground to shape like any scissor blade, and are too costly to be discarded rather than resharpened. The welded blade becomes, of course, an integral part of the shank, and the completed instrument therefore presents no advantages over scissors having blades of tool steel throughout. The practical utility of inventions of this class requires that the scissors shanks and blades be of such design and construction as to permit of a low initial cost of production; the cost of replacement blades to the user should be considerably lower than the expense of grinding; the blade should be readily and securely attachable to the shank and conveniently detachable therefrom, without the use of tools and by persons unskilled in mechanical matters; and this attachment should be possible without taking the shanks apart or removing the king-pin.

The cutting edges of scissors commonly define a helical or three dimensional curve, the

curvature depending upon the type of scissors and the work for which they are designed. To grind this curve into each blade would involve a prohibitive expense where the blade is to be discarded after the first dulling, and I therefore make my blade straight, but so flexible as to be conformable to any curve or twist normally defined by the permanent shank on which the blade is mounted. To mount this blade in cutting position each shank is provided with a longitudinal bead or undercut rail extending along its operative edge and conforming to its curvature, and each blade is provided with a corresponding longitudinal slotted recess. The blade can therefore be slid lengthwise over the bead, and because of its universal flexibility, conforms perfectly to the curvature.

The blade of the present invention, in order that it may possess the universal flexibility so important if it is to conform to the curvature of the shank is of small transverse dimensions—thus a blade for barbers' scissors of average size is about 5/64 of an inch high and about 1/32 of an inch wide. Such a blade is indeed a specially shaped steel wire. According to the present invention I have provided a method whereby such a wire can be rolled, drawn, tempered, ground and cut to length in a continuous operation.

In the accompanying drawings I have illustrated the various steps followed in making the blade.

In these drawings Figure 1 is an enlarged section of one form of the material from which the blade may be made; Figure 2 is an enlarged fragmentary section of a pair of rolls for preliminarily forming the material shown in Figure 1; Figure 3 is an enlarged section showing the form of the blade material after having passed through the rolls shown in Figure 2; Figure 4 is an enlarged fragmentary section of a second pair of rolls and an enlarged elevation of a coacting mandrel and support therefor, for further forming the blade material; Figure 5 is an enlarged section showing the form of the blade material after having passed through the rolls and over the mandrel shown in Fig-

ure 4; Figure 6 is an enlarged fragmentary view of chilling dies for hardening and planishing the blade material; Figure 7 is an enlarged section of a modified form of material from which the blade may be drawn; Figure 8 is an enlarged fragmentary section of a pair of rolls for handling the material of Figure 7; Figure 9 is an enlarged section of the blade material after having passed through the rolls of Figure 8; Figure 10 is an enlarged elevation of chilling dies for finally forming, hardening and planishing the blade material after having passed through the rolls of Figure 8, and Figure 11 is an enlarged section of the blade material after having been drawn through the forming, hardening and planishing dies of Figure 10.

In accordance with the present invention the blades are manufactured in lengths in the following manner: Material of triangular cross section such as shown in Figure 1 is passed, either hot or annealed, through rolls 1-1 (Figure 2), bringing it to the general form shown in Figure 3. It is then re-heated or re-annealed and passed between rolls 2-2 (Figure 4) and over mandrel 3, mounted in support 4 (Figure 4), thereby bringing it to the form shown in Figure 5. After passing through rolls 2-2 and over mandrel 3, and while still hot or after having been re-heated by passing through a hardening furnace, it is drawn through dies 5-5 and over mandrel 6 (Figure 6). These dies are preferably formed with a bell-mouth entrance 7, and may be of the water-cooled type. Their function is to chill, harden and planish the strip and prevent distortion thereof. Thereafter the strip may be tempered in any well-known manner, as by feeding it through a bath of heated oil. On account of the small cross-sectional area and consequent lack of rigidity of the strip while hot, it may be found desirable to feed it downward, rather than horizontally, through the forming rolls. After being tempered, the strip is fed into contact with an abrasive wheel, which grinds the face 8 to form the cutting edge 9. Any cut outs and notches required to facilitate the mounting of the blade upon the scissors shank as illustrated in my co-pending application, Serial No. 173,528, are then ground out and the blades cut to length also by a grinding operation.

In Figure 7 is shown a material of somewhat different initial shape. This is similarly passed while hot or annealed through rolls 10-10 (Figure 8), bringing it to the intermediate form shown in Figure 9. In this intermediate form it is drawn through a furnace and thence through dies 11-11 (Figure 10) and over mandrel 12 to draw close it to the form shown in Figure 11 and to chill, harden and planish the material in such form. It will be noted that with this

modified method, the passage of the strip material through one set of rolls is eliminated, thus rendering the process more economical.

The blades may be so cheaply made by this method that when dulled they can be replaced for much less than the cost of re-grinding.

This application is a division of my co-pending application, Serial No. 173,528, filed March 7, 1927.

I claim:

1. The method of making detachable blades for scissors which comprises passing a continuous strip of metal between rolls to form a continuous slotted recess extending longitudinally therethrough, drawing the shaped strip through hardening and planishing dies, tempering the strip, grinding a cutting edge thereon and then cutting the strip into unit lengths.

2. The method of making detachable blades for scissors in a continuous operation which consists in passing a wire-like strip of metal downward between rolls to form a longitudinal passage therethrough, heating such slotted strip by passing it through a furnace, hardening and polishing it by drawing it through dies, tempering and grinding a cutting edge thereon and then cutting the strip into unit lengths.

In testimony whereof I affix my signature.

MORGAN PARKER.
